UNITED STATES PATENT OFFICE.

FREDERICK E. MUELLER AND GEORGE R. BOTT, OF NEW YORK, N. Y., ASSIGNEES
TO NORMA-HOFFMAN BEARINGS CORPORATION, OF NEW YORK, N. Y., A CORPORA-
TION OF NEW YORK.

TEXTILE SPINDLE.

Application filed April 9, 1920. Serial No. 372,400.

To all whom it may concern:

Be it known that we, FREDERICK E. MUELLER and GEORGE R. BOTT, citizens of the United States, and residents of the city of New York, in the county and State of New York, have invented certain new and useful Improvements in Textile Spindles, of which the following is a description.

The present invention relates to spindles, 10 and comprehends in its generic aspect certain improvements in silk and cotton spinning spindles of that general type commonly known in the art as "self-centering" spindles, whereby a mechanically, practical and commercially efficient spindle will be produced.

In spindles of the class above mentioned, 20 in case an unbalanced load is imposed upon the spindle, or, if the latter should contain slight mechanical imperfections, owing to the fact that the load is located above the driving band, an oscillatory or gyratory motion is set up around the normal center of gravity. It is primarily due to the lateral movement of the spindle whirl and 25 its bolster, when operating at high speeds, that the small ball bearings with which such spindles have heretofore been equipped, fail to meet service requirements in a satisfactory manner.

Therefore, the leading object and purpose of our invention is to provide an improved spindle construction and mounting of the self-centering type, and in combination therewith, an improved ball bearing 35 support for the spindle whirl in which the balls are of adequate size, whereby the bearing will reliably and efficiently withstand severe duty. It has been successfully demonstrated in practice, that by reason of 40 the improvements hereinafter described, an increased, uniform spindle speed may be maintained and with a minimum of friction even when operating at a maximum speed, thus resulting not only in an increased output 45 but also in a better quality of yarn, in comparison with the production of the several types of spinning spindles now in general use.

In eliminating the above noted objection 50 to such spindles, as heretofore constructed, we have provided a novel, as well as simple and compact arrangement of the several elements in combination with each other, and have thereby attained a maximum operating efficiency, and at the same time have produced 55 a spindle construction which will result in

appreciable economy in maintenance cost. It is likewise an important object of the invention to provide a spindle as above characterized, which will result in a material reduction in power costs by the elimination of excessive friction, the several parts of which are of relatively simple form, may be easily and quickly removed or replaced, not liable to get out of order when operatively assembled, and are capable of quantity production at comparatively small manufacturing cost.

Having the aforementioned objects in view, the present invention comprehends 70 certain novel and improved combinations of mechanical elements, and the structural characteristics thereof, as will be more fully developed in the following description and subsequently incorporated in the subjoined 75 claims.

In the accompanying drawings wherein we have illustrated several practical embodiments of our invention and in which like reference characters designate corresponding parts throughout the several views,

Figure 1 is a vertical sectional view of a silk spinning spindle illustrating one embodiment of our invention;

Figure 2 is a similar view of a slightly 85 modified form of the device;

Figure 3 is a horizontal section taken on the line 3—3 of Figure 1;

Figure 4 is a view similar to Fig. 1 showing another form of the cotton spinning 90 spindle;

Figure 5 is a section taken on the line 5—5 of Figure 4;

Figure 6 is a detail perspective view of the bolster support shown in Figure 4.

It has been proposed by those familiar with the necessities arising in the operation and maintenance of spinning spindles, to provide such spindles with ball bearings. Numerous attempts have been made to provide a practical and efficient arrangement of bearings for such spindles, but in view of the small size of the spindle whirl, the bearing balls of necessity have been limited 100 in size and were therefore incapable of withstanding the severe duty to which such spindles are subjected. It was impossible to maintain a uniform spindle speed or to operate the spindle at high speeds without resulting in the rapid wearing out of such 105 small bearings. As is well known, such spinning spindles have an oscillating move-

ment about the normal center of gravity, and therefore the small bearing balls as heretofore used would track in different circumferential paths whereby the speed 5 possibilities would be reduced and vibration accompanied with unequal wear upon the bearings would result. Accordingly, such spindle bearings have proved to be entirely impractical.

10 We aim, by means of our present improvements, to obviate the deficiencies of prior spindles as above referred to and in Figure 1 of the drawings we have disclosed one embodiment of our invention as applied 15 to a silk spinning spindle. In this figure, 5 designates the spindle supporting rail having an opening to receive the shank 7 of a socket member 6. This bolster is formed with a chamber 8 to receive a suitable 20 lubricating oil, said bolster being provided with a tubular upstanding portion 9 and a port or opening 10 affording communication between said tubular portion and the chamber 8. A piece of absorbent material 11 is 25 arranged in the lower end of the bore of the tubular portion 9 over the port 10 and serves to prevent flooding of the chamber 8 or the entrance of foreign matter into said chamber. The upper end of the tube 9 is 30 closed by a removable plug 12.

The socket member 6 is formed with a bore or socket 13 extending axially into the shank 7. This socket receives the lower end of the spindle bolster 14, said support 35 being formed with a diametrically enlarged portion or flange 15 which rests upon the base wall of the chamber 8 and limits the movement of the support into the socket 13. The bolster 14 is loosely mounted in the 40 socket member and may rotate with respect thereto.

A sleeve whirl 16 surrounds the support 14 and at its upper end is reduced as at 17 and fixed to the lower end of the spindle 18. 45 The inner diameter of the sleeve wall 16 is appreciably greater than the diameter of the support 14. The lower end of the whirl is formed with an outwardly projecting flange 19 and extends downwardly into the 50 chamber 8.

Ball bearings, generally designated by the numerals 20 and 21 respectively, are interposed between the lower and upper ends of the spindle whirl 16 and the support 14. 55 Each of these bearings preferably includes inner and outer bearing rings 22 and 23 respectively, each of which is formed with a circumferential raceway 24 and 25 to receive the bearing balls 26. Each bearing is 60 further provided with a continuous cage ring 27 which is of channel shaped form in cross section to provide the side flanges 28. The inner face of each flange 28 is provided at suitably spaced points with the 65 cavities or seats 29 to receive the bearing

balls 26. The flanges 28 thus normally retain the bearing balls at their axes of rotation and guide the balls in their path.

Various other types of ball bearings may, however, be employed. The inner bearing 70 ring of the lower bearing 20 is seated upon the flange 15 and suitably fixed to the support while the corresponding ring of the upper bearing 21 is engaged upon an annular shoulder 30 formed upon the support and also fixed thereto. The outer bearing rings are suitably secured to the wall of the whirl 16. Preferably, nuts 22' are threaded upon the support and engage the inner race rings to retain the latter in position. A sleeve 16' 80 is arranged within the whirl 16, and fits snugly against the wall thereof. The opposite ends of this sleeve abut against the outer race rings 23 of the respective ball bearing units 20 and 21.

The support 14 is formed with an axial bore 31 which opens upon the upper end face thereof and extends downwardly below the flange 15. A plurality of transverse openings 32 are formed through this flange and afford communication between the bore 31 of the support and the chamber 8. Within the bore 31, an absorbent wick 33 is disposed and at its upper end is loosened or unraveled so that the lubricating oil which is drawn 90 upwardly through the absorbent wick by capillary action, will be distributed radially upon all parts of the upper bearing 21. It will be noted that the upper end of the wick 33 is engaged against the lower end face of 95 the spindle 18 so that in the rotation of the spindle, by the action of centrifugal force, the oil is radially distributed upon the parts of the bearing 21. This centrifugal force 100 in connection with the capillary action 105 subserves the function of a pump acting to continuously draw the lubricant upward from the chamber 8. The excess oil will then flow downwardly and upon the elements of the lower bearing 20 whereby the latter will likewise be thoroughly lubricated. Such oil as is not consumed will drip back into the chamber 8. In order to 110 prevent the violent agitation of the oil in this chamber upon rotation of the whirl 16 we have provided a baffle plate 34 arranged 115 in the chamber between the base wall thereof and the lower end of the whirl. This plate is of sheet metal and at its perimeter is formed with a plurality of downwardly 120 projecting lugs 35 struck from the plate which serve to support the baffle plate in its proper position. The central opening 36 in said plate is of somewhat greater diameter than the diameter of the flange 15 so that the oil dripping from the bearing 20 may have free passage into the chamber and the ports 32 which communicate therewith. In this manner, it will be seen that a continuous 125 circulation of lubricating oil is 130

5 maintained between the chamber 8 and the upper and lower sets of ball bearings which rotatably support the whirl upon the support 14. In order to yieldingly hold the spindle in normal perpendicular position, an expansion spring 37 is disposed around the shank 7 of the bolster 6 and bears at its upper end against a washer plate 38 which has sliding engagement with the under 10 side of the rail 5. A nut 39 is threaded upon the lower end of the shank 7 and the other end of the spring 37 is seated against the washer plate 40 which loosely surrounds said shank. By adjusting the nut 39, it 15 will be readily seen that the tension of the spring 37 may be regulated as desired. It will be understood that the provision of this spring 37 constitutes no part of the present invention, as it is well known in the art 20 and commonly used in connection with silk spinning spindles.

In Figure 2 of the drawings we have shown a slightly different form of the sleeve whirl which surrounds the support 14. In 25 this instance, the medial portion of the whirl which is engaged by the driving band is reduced in diameter as at 41 so that its inner surface is but slightly spaced from the periphery of the support. At its upper end, 30 the whirl is formed with a diametrically enlarged portion 42 in which a spindle base 43 is fixed. The upper ball bearing 21' is also arranged in this enlarged portion of the spindle whirl and bears the same relation 35 to the support as in the construction above described.

The spindle whirl as shown in Figure 2 is further provided with a diametrically enlarged lower end 44 which extends into the 40 lubricant receiving chamber 45 of the bolster which is mounted in the supporting rail. This enlarged lower end of the whirl contains the lower ball bearing 20'. It will thus be seen that by such construction, a whirl of 45 relatively small diameter is obtained while at the same time the two sets of bearings arranged respectively above and below the whirl center, in this embodiment, have bearing balls and races of relatively large diameter. In this case also there is a continuous 50 circulation of lubricating oil maintained between the lubricant containing chamber of the two sets of bearings as in the construction shown in Figure 1. It will, of course, 55 be apparent that the spindle whirl might also be made in various other diameters between the two extremes shown in Figures 1 and 2.

60 As shown in Figure 2 of the drawings, instead of mounting the bolster in a continuous rail, it may be arranged in an opening provided in one end of a bracket member 46, the other end of the bracket being pivotally mounted upon the upper end of a supporting strut 47 which is secured rigidly to

the rail. The pivotal or turning movement of the bracket is yieldingly retarded or cushioned by a spring 49 surrounding the standard 47 and having one of its ends fixed to the rail, while the other end of said spring is 70 secured to the bracket 46. In Figure 2 we have shown the support 14 extending entirely through the shank of the bolster and tightly secured in place by a nut 14' threaded upon the lower end of said support. When 75 the bolster is thus mounted in a yieldingly held bracket, the use of the spring surrounding the shank of the bolster may be dispensed with if desired.

In Figure 4 of the drawings we have 80 shown an alternative form of the cotton spinning spindle in which two sets of ball bearings are provided. In this arrangement the socket member 65 is securely fixed in the bracket 46, said socket member having a 85 relatively short shank 66 provided with the bore 67 as in the construction shown in Figure 1. In this case, the bolster 68 has a shoulder 69 resting upon the upper end of the supporting member 70. This member 90 is formed with spaced vertical legs 71, the lower ends of which are laterally extended as at 72 and fixed to the annular flange 73 formed upon the wall of the lubricant receiving chamber 74. In spaced relation to 95 the lower end of the bolster, said bolster is provided with a collar 75 having equidistantly spaced peripheral recesses 76 through which the legs 71 loosely extend. The inner bearing ring 77 of the lower ball bearing 100 arranged within the base portion of the whirl 78 is fixed upon the periphery of this collar and closes the outer sides of the recesses 76 therein. In this case the whirl 78 105 is similar in its general form and construction to the whirl shown in Figure 2 of the drawings, the upper ball bearing 79 being disposed within the enlarged upper end of said whirl.

In this case also the bolster 68 is axially bored to receive the lubricant absorbent wick 80 and the lower end of said bolster which extends into the bore 67 of the socket member 65, is provided with the transverse opening 81 into which the lower end of the wick extends. Thus, it will be seen that the lubricant is fed into the chamber 74 and the bore 67 and is carried upwardly by the wick and distributed in the manner heretofore described to the upper ball bearing 79 from which it gravitates downwardly upon the parts of the lower ball bearing and hence back into the chamber 74.

We have found that the tendency of the 125 balls to shift upon the track surfaces and to therefore track in different circumferential paths, may be effectively counteracted by the provision of the cage 27 having the side flanges 28. These side flanges by their holding action upon the several balls at their 130

axes of rotation, cause all of the balls to move in unison. By the provision of a bearing of this construction, we are enabled to use bearing balls which are of comparatively large size, the enlarged portions of the spindle whirl affording ample space within which such large bearings may be properly mounted and arranged. Heretofore, bearings having balls of very small size have been used, but such bearings have been found impracticable as they are incapable of successfully withstanding the severe duty to which ball bearings used in this connection are necessarily subjected. In other words, they do not afford a sufficiently extensive bearing surface to properly support the spindle whirl, and soon lose their anti-frictional qualities, when it is attempted to operate the spindle at the higher speeds.

From the foregoing description taken in connection with the accompanying drawings, the several illustrated and described embodiments of the invention will be readily understood. In actual practice, it has been found possible to operate a spindle equipped with our improvements particularly as disclosed in Figure 1, at a very high speed. It will thus be seen that our present improvements will materially increase the output of each spindle and in view of the fact that an absolute uniformity in speed is maintained, the quality of the product will also be appreciably enhanced. It is also to be noted that in any one of the several constructions to which we have herein referred, the various parts can be easily and quickly assembled or disassembled and replaced by new parts when necessary.

In the preceding description and the accompanying drawings we have disclosed several practical embodiments of the invention, which, however, may likewise be ex-

emplified in numerous other alternative constructions. Accordingly the invention as herein claimed is to be considered as inclusive of all legitimate equivalents for the various elements employed as well as other contemplated arrangements thereof, which may satisfactorily accomplish the desired results.

We claim:—

1. A spindle mounting comprising a socket member having a lubricant chamber, a bolster fitted therein and having a lubricant passage, a whirl extending about said bolster and fitting into said chamber, a spindle carried by said whirl, anti-friction bearings between said whirl and bolster, an annular baffle plate situated in said lubricant chamber having its inner edge spaced from the bolster and outer edge spaced from the side walls of the socket, and means for supporting said baffle plate above the bottom of the socket.

2. A spindle, a bolster, a socket therefor, a sleeve whirl surrounding said bolster and having diametrically enlarged portions above and below the driving band, ball bearings arranged within said enlarged portions of said whirl, said socket having a lubricant receiving chamber, means for automatically maintaining a continuous circulation of the lubricant between said chamber and the two bearings, an annular baffle arranged in said chamber to prevent agitation of the lubricant having its inner edge spaced from the bolster and outer edge spaced from the side walls of the socket, and means for supporting said baffle plate above the bottom of the socket.

In testimony that we claim the foregoing as our invention, we have signed our names.

FREDERICK E. MUELLER.
GEORGE R. BOTT.
